UNITED STATES PATENT OFFICE.

WINFIELD S. GROVE, OF MANILA, PHILIPPINE ISLANDS.

FIBER-CLEANING MACHINE.

Application filed December 1, 1920. Serial No. 427,539.

To all whom it may concern:

Be it known that I, WINFIELD S. GROVE, a citizen of the United States, and a resident of the city of Manila, Philippine Islands, have invented certain new and useful Improvements in Fiber-Cleaning Machines, of which the following is a specification.

The invention relates to machines for removing pulp and waste material from fibrous vegetable substances and it is also adaptable for use in the cleaning of the fibers in the substance. The machine is particularly adaptable for obtaining hemp fiber, such as manila hemp, from the original leaves or strips and it is also adaptable for treating other fibrous substances such as sisal, maguey, pineapple leaves or the like.

The object of the present invention is to construct a machine which is suitable for the purposes desired that will be cheap and easy to manufacture and by means of which there can be obtained a large quantity of treated or cleaned fiber at a comparatively small cost.

According to the machine which is the subject of the present application use is made of gripping jaws that pull the stock through a set of decorticating tools arranged at or near the end of the path of travel of the gripping jaws.

As showing certain specific embodiments of the invention reference is made to the drawings forming a part of this specification and in which drawings,

Figure 1 is a longitudinally extending vertical sectional view taken as on the line 1-1 of Figure 2.

Figure 2 is a plan view partially broken away of the machine shown in Figure 1.

Figure 3 is an end view partially broken away of the same machine.

Figure 4 is a vertical sectional view taken as on the line 4-4 of Figure 2.

Figure 5 is a longitudinally extending vertical sectional view partially broken away showing a machine embodying the invention in a somewhat different form from that shown in Figures 1 to 4.

Figure 6 is a vertical sectional view partially broken away taken as on the line 6-6 of Figure 7 looking in the direction of the arrows.

Figure 7 is a plan view partially broken away of the machine shown in Figure 5.

Figure 8 is a detailed view illustrating the position of certain of the parts at the time when one of the sets of gripping jaws is in position to receive therein a piece of stock to be treated; and

Figure 9 is a view taken as on the line 9-9 of Figure 7.

In the form of machine shown in Figures 1 to 4 there is a main frame 1 which comprises transversely extending upright end-members or housings 2 and 3 which are connected by longitudinally extending members 4 located midway of their height, and a centrally arranged longitudinally extending member 5. This member 5 serves as a suitable construction to provide a track or raceway 6, 6 and may be in the form of a channel the upstanding legs of which provide the track members. A carriage 7 having wheels or rollers 8 is mounted upon the track and there is provided a screw means 9 for propelling the carriage along the track. This screw is mounted in bearings 10 that are carried by the end-members or housings 2, and it engages a nut-member 7^a on the carriage and is driven from the belt 11 through the medium of tight and loose pulleys 11^a, shaft 11^b, the reversing gear 12, the shaft 13 and the chain and gear mechanism 14. Due to the reversing gear at 12 this screw can be rotated in opposite directions so as to impart a reciprocating movement to the carriage. The reversing gear 12 comprises as a part thereof a shifting sleeve 15 that is under the control of a lever 16. The lever 16 carries at the upper end thereof a spring pressed buffer 17 that is arranged in the path of a stop or projection 18 that is on the carriage. The lever 16 is also connected through the medium of a link 19 to another lever 20 which is at the other end of the machine. The lever 20 also has a spring pressed buffer 21 which is in the path of a stop or

100

projection 22 that is on the carriage. As the spring pressed buffer 21 is engaged and forced toward the left by the stop 22 it will force the upper end of the lever 20 to the left thus exerting a pull on the link 19 and forcing the lower end of the lever 16 and sleeve 15 from the left toward the right into the position shown in Figure 1. When in this position the screw is being driven 10 so as to move the carriage in the direction of the arrow A shown in said Figure 1. When the carriage is moved to the right in the direction of the arrow a sufficient distance the stop 18 will engage the spring 15 pressed buffer 17 and force the lower end of the lever 16 and sleeve 15 from their present position to the left whereby the screw will be rotated in the opposite direction so as to move the carriage back in a 20 direction opposite to that indicated by the arrow.

In the form of apparatus shown in these figures there are four sets of transversely extending decorticating tools each of which 25 sets of tools is designated by the reference character 23. There are two sets of decorticating tools at each end of the machine, one set at each end of the machine being at one side of the longitudinal center of the 30 machine and the other set being at the other side of the longitudinal center of the machine. There are also four sets of stock gripping jaws each of these sets being designated by the reference character 24. Each 35 set of these gripping jaws is arranged so as to cooperate with one of the sets of decorticating tools 23. There are two sets of gripping jaws at each end of the carriage 7 one set at each end of the carriage being 40 at one side of the longitudinal center of the machine and the other set being at the other side of the longitudinal center of the machine.

Each set of decorticating tools preferably 45 comprises a movable knife 25 and a resisting member 26 opposed thereto. The resisting member is preferably fixedly secured in place although it may be made a movable member if desired. The knife, however, is 50 preferably made movable so as to permit of the ready entrance of a piece of stock into the space between said decorticating tools when the knife thereof is out of operative position. The knife 25 may be moved from 55 and toward operative position as through the medium of the eccentric shaft construction 27 that is operated by the handle 28.

In Figure 1 the jaws 24 at the left hand 60 side of the machine are shown in the position which they occupy at about the time the piece of stock is about to be drawn through the space between the decorticating tools. The jaws are held in gripping position by means of a sliding bolt 29 which is forced 65 into position by the operator pressing

against the handle 30. This handle 30 has a transversely extending bearing 31 which serves to simultaneously force into locking position the sliding bolts 29 that are on opposite sides of the machine. When the 70 sliding bolt is in the position shown in Figure 1 it will be observed that the gripping jaws at the right hand end of the carriage are permitted to be held open by means of the springs 32 that are located between the 75 jaws.

The form of apparatus shown in Figures 5 to 9 inclusive comprises transversely extending uprights or housing members 2 and 3 and the centrally arranged longitudinally extending member 5 that provides the tracks for the carriage 33. This form of machine has four sets of decorticating tools 34 one in each corner of the machine. In other words, there are two sets of decorticating tools at each end of the machine with one of the sets at one end of the machine at one side of the longitudinal center of the machine and the other set at the same end at the other side of the longitudinal center of the machine. The carriage has gripping jaws that cooperate with the several sets of decorticating tools; in other words, there are four sets of stock gripping jaws 35, two at each end of the carriage, with one set of the jaws at each end being at one side of the longitudinal center of the machine and the other set of jaws on the other side of the longitudinal center of the machine. The carriage is also provided with hand operating means 36 which serves to lock or hold in gripping position the jaws at one end of the carriage and also to hold in open position the jaws at the other end of the carriage. This is accomplished 105 through the medium of the handle 37 which is pivotally mounted on the carriage at 38 and to this handle there is connected a set of links 39 which is pivotally connected at 40 to the jaws at one end of the carriage and 110 at 41 to the handle.

A corresponding construction is provided between the handle and the jaws on the other side of the carriage and when the link 14 holding any of the jaws in gripping position the link constitutes a part of a toggle link construction of which the handle constitutes another part. A set of stops 42 is provided on the carriage to serve as limiting means whereby the toggle link members can 115 be moved only a slight distance past the center as they are moved to locking position. It will thus be observed that when the jaws at the left hand side of the machine are being held in gripping or closed position the jaws at the right hand of the machine are held open by the mechanism just described. There is located adjacent to each of the sets of decorticating tools 34 a set of rollers 43. These rollers may be referred 120 125 130

to as auxiliary feed rollers since their function is to assist the gripping jaws in pulling a piece of stock being operated upon through the space between the decorticating tools. 5 The rollers 43 are preferably spring pressed toward each other so that they can yield and can conform to the work, but they are mounted upon the free ends of bell crank levers 44 and 45. Each of these levers has 10 a part arranged in the path of movement of the carriage 33, that is they are arranged in the path of the movement of the vertically extending members 46 so that as the jaws travel in the last portion of their movement 15 toward the decorticating tools the feed rollers will be forced apart against the pressure of the springs due to the vertically extending members or ears 46 engaging the levers 44 and 45 whereby the gripping jaws 20 that are being moved toward the decorticating tools will be permitted to pass between the rollers. The decorticating tools comprise the yieldable knife 47 and the resisting member 48, the latter of which is preferably fixed on the end member of the machine. The knife is preferably mounted in a swinging housing 49 so that it can be swung away from the gripping jaw to the position shown, for example, at the right 25 hand side of Figure 5 or in Figure 8. The knife when in operative position is normally spring pressed toward the resisting member 48 by means of the spring members 50, the compression of which is controlled by means 30 of an adjusting nut 51.

In Figure 8 the rollers 43 which may be referred to as auxiliary feed rollers are shown in the position which they occupy when the gripping jaws are between them 40 and are to receive a piece of stock which can be caused to enter the space between the decorticating tools, due to the fact that one of the decorticating tools has been moved from operative position. The construction 45 of the machine at each side thereof is substantially the same and also the construction of the machine at each end thereof is substantially the same. The swinging knife member is retained in operative position by 50 means of a spring 52 (see Figures 6 and 7). The upper knife member or decorticating tool 47 is slidably mounted in the pivotal members 53 that together in effect serve as the pivotal housing for the sliding member 55. The members 53 have pins or journals 54 and 55 which are secured in place as through the medium of pins 56. The journals 54 and 55 are mounted respectively in bearings 57 and 58 that are on the end members 60 or housings of the main frame of the machine. Upon the pivotal members 53 there are mounted screws 59 around which the springs 50 are located. The lower end 65 of each of these springs 50 engages a yoke 60 at the upper end of the knife 47, thus

providing a comparatively simple but rigid construction for holding the knife in place and also for permitting the knife to be withdrawn from operative position.

Reference has heretofore been made to the spring 52. It will be observed that one end of this spring is secured at 61 to a boss or ear on the bearing 58 and that the other end of the spring is secured at 62 to the pin 55, the tension of this spring being sufficient to normally tend to press and retain the knife 47 and the pivotal housing therefor in upright position. The housing engages suitable stops 63 whereby while the stock is being pulled through the space between the decorticating tools the knife 47 and the housing therefor will be maintained in proper position. The means for operating the carriage that carries the gripping jaws comprises a screw 64 that is driven through the medium of the tight and loose pulley construction at 65. The shifting of the belts that operate the tight pulley is under the control of the construction which comprises shifting arms 66 and 67, the cam 68, the link 69, the arm 70, the shaft 71, arm 72, link 73 and the lever 74. This lever 74 has at the upper end thereof a spring buffer 75 which is engaged by the stop 76 at one end of the carriage 33 so as to shift one of the belts on the tight pulley when the carriage reaches one end of its travel. The lever 74 is connected by means of a link 77 to a companion lever 78 that also has a spring buffer 79 to engage a stop 80 at the other end of the carriage whereby when the carriage reaches the end of its travel in the opposite direction the other belt will be shifted on the tight pulley thus causing the carriage to travel in the proper direction. If desired a receiving pan or trough can be secured in place underneath the travel of the jaws to receive any débris or substance falling from the stock being treated. This pan is indicated in Figure 4 by the reference character 81 and is secured in place to the central track construction by means of screws 82.

The improvements herein set forth are not limited to the precise construction and arrangement shown and described for they may be embodied in various forms and modifications without departing from the spirit and scope of the invention.

What I claim is:

1. A machine of the class described comprising in combination a main frame having standards at each end thereof, a centrally arranged longitudinally extending track thereupon, a carriage mounted upon said track, said carriage having four sets of stock gripping jaws, two sets at each end of the carriage, one set being at one side of the longitudinal center of the machine and the other set at the other side thereof, corre- 130

sponding sets of decorticating tools, two at each end of the main frame, one set being at one side of the longitudinal center of the machine and the other set being at the other side thereof, and means for reciprocating the carriage.

2. A machine of the class described comprising in combination a longitudinally extending member providing a track, two sets 10 of decorticating tools at one end of the track and on opposite sides thereof, a carriage mounted so as to move along said track, said carriage having gripping jaws at opposite sides thereof in cooperative relationship 15 with respect to said decorticating tools, and means for reciprocating said carriage and jaws toward and from the decorticating tools.

3. A machine of the class described comprising in combination a longitudinally extending member providing a track, a carriage mounted upon said track, means for reciprocating said carriage along said track, gripping jaws on said carriage, decorticating 20 tools located at an end of said track, feed rollers cooperating with said gripping jaws, said rollers being constructed and arranged so as to permit the gripping jaws to pass into the space between them when 25 the rollers are moved away from each other.

4. A machine of the class described comprising in combination a main frame supporting at each side thereof decorticating tools that are mounted so that the tools of 35 each set can be moved relatively to each other to permit of the insertion of a piece of stock between them, a longitudinally extending member providing thereupon a centrally arranged track, a carriage mounted 40 so as to move along said track and carrying gripping jaws arranged in cooperative relation with respect to said decorticating tools, and means on said frame for reciprocating the carriage which means is controlled in its operation by said carriage.

5. A machine of the class described comprising in combination a main frame having a centrally arranged track member extending longitudinally of the frame, transversely 50 extending end-members, a plurality of sets of decorticating tools, one of said sets being located at one side of the longitudinal center of the machine and the other of said sets being located at the other side of the 55 longitudinal center of the machine, a carriage mounted so as to slide along said track, said carriage having at each end thereof gripping jaws arranged to cooperate with the decorticating tools, and a common jaw 60 closing means constructed and arranged so as to hold the jaws at one end of the carriage in gripping position, a centrally arranged longitudinally extending screw for reciprocating the carriage along the track, 65 a power means for operating said screw,

and means under the control of the carriage for determining in what direction said screw shall be rotated.

6. A machine of the class described comprising in combination transversely extending decorticating tools arranged so that they can be moved relatively toward and from each other so as to permit the introduction of stock into the space between the tools, gripping jaws mounted so as to move toward and from the decorticating tools, and auxiliary feed rollers arranged on the delivery side of said tools so as to assist the jaws in pulling a piece of stock being treated through the space between said decorticating tools when the latter are in operative relation in respect to each other, the auxiliary feed rollers being mounted so that the gripping jaws can pass into the space between the rollers when the gripping jaws are about to be supplied with stock to be treated.

7. A machine of the class described comprising in combination a main frame having transversely extending end housing members and a longitudinally extending track member secured to said housing members, a set of transversely extending decorticating tools mounted upon one of said housing members which tools are mounted so that they can be moved from operative position relatively 90 to each other so as to receive between them a piece of stock to be treated, a carriage, means for reciprocating said carriage along said track, jaws carried by said carriage and arranged to grip a piece of stock and pull it through the space between said decorticating tools, and rollers mounted on the frame of the machine and driven so as to assist the jaws in pulling the stock being treated, said rollers being mounted so that during the final part of the approach of the jaws toward the decorticating tools the rollers will be moved away from each other to permit the jaws to pass between them, and a common means for actuating said rollers 100 and for reciprocating the carriage carrying the jaws.

8. A machine of the class described comprising in combination a main frame having transversely extending end-members, a longitudinally extending member providing a track, a set of transversely extending decorticating tools at each end of the frame, a set of transversely extending feed rollers located adjacent to each set of decorticating tools, a carriage on said track, means for reciprocating said carriage between said sets of decorticating tools, stock gripping jaws at each end of the carriage, means for locking one set of said jaws at one end of the carriage in closed position and for permitting the jaws at the other end of the carriage to be in open position, rocker arms supporting the feed rollers which rocker arms are constructed and arranged so that 115 120 125 130

they will be engaged by the carriage as it approaches the decorticating tools at the end of the machine toward which the carriage is being moved whereby the gripping jaws can pass between the feed rollers, reversing means having members arranged in the path of travel of the carriage for controlling the operation of the means for reciprocating the

carriage, and means for operating the feed rollers.

This specification signed and witnessed this 20th day of September A. D., 1920.
